HORSESHOE

Rollin C. Mitchell, Spokane, Wash.

Application December 16, 1943, Serial No. 514,514

4 Claims. (Cl. 168—33)

This invention relates to horse shoes and more particularly to a shoe for race horses. Shoes for race horses must be of light weight and since race horses run upon tracks which may be dry or muddy, it is necessary to provide a horse with shoes suitable to the condition of the track over which a race is to be run.

Therefore, one object of the invention is to provide a shoe which is especially adapted for use by race horses since it has a light body formed of aluminum and calks which are detachably applied and may be easily and quickly applied, according to the type of track over which the horses must run during a race.

Another object of the invention is to provide the body of the shoe with inserts of hard metal in which sockets may be formed to receive threaded stems of calks and without likelihood of splitting as would be the case if the calks were screwed into sockets formed directly in the body of an aluminum shoe.

Another object of the invention is to provide a calk removably carried by an insert in such manner that it will be prevented from working downwardly or having turning movement which would loosen it.

In the accompanying drawing:

Fig. 1 is a perspective view of a horse shoe having the improved construction.

Fig. 2 is a fragmentary sectional view taken along an enlarged scale, on the line 2—2 of Fig. 1.

Fig. 3 is a group view in perspective showing a calk for a muddy track removed from the shoe.

Fig. 4 is a view similar to Fig. 3, showing a calk for a dry track.

Fig. 5 is a fragmentary sectional view showing the insert cast into the heel of a shoe.

The present horse shoe, indicated in general by the numeral 1, is of the type used upon race horses and is formed of aluminum or similar metal so that it will be light in weight. This shoe is provided with a toe calk 2 of conventional form and the heel portions are formed with enlargements 3 which project downwardly and have embedded therein inserts or blocks 4 which are formed of steel or other suitable hard metal. The inserts are of frusto conical shape, as shown in Figs. 2 and 4 of the drawing, and each is formed at its outer or lower end with a flat disc-shaped head 5 which has flat contacting engagement with the lower end face of the enlargement in which the insert is embedded. The heads have flat under faces and each is formed at diametrically opposite points with recesses 6 to receive lugs 7 formed integral with the enlarge-

ments 3 and serving to brace the inserts against turning movement in case they should tend to loosen when the shoe is in use. A threaded socket 8 is formed in each insert axially thereof to receive the threaded stem of a calk.

The two heel calks, indicated in general by the numerals 9 and 10, are formed of steel or other suitable metal and each has a disc-shaped body from which extends the threaded stem 11 which is screwed into the socket of the companion insert, notches or recesses 12 being formed in the peripheral portion of the body of the calk in diametrically opposed relation to each other to receive a wrench by means of which the calk is screwed into place. About the stem of each calk the body is formed with a circular recess 13 to receive a locking washer 14 of the split-washer type, and from an inspection of Fig. 2, it will be seen that when the calk is screwed tightly into place, the washer will be flattened and have biting engagement with the calk and the confronting lower face of the insert and resist loosening of the calk.

The calk 9 carried by the heel at the outer side of the shoe is provided with a spike 15 which extends outwardly or downwardly therefrom and is tapered toward its lower end, and, by referring to Figs. 1 and 2, it will be seen that when the calk is applied to the shoe, turning thereof while screwing it into place is stopped with the calk disposed in the plane of the length of the shoe. The calk at the inner side of the shoe is identical in construction to that used at the outer side of the shoe but carries no spike and the under face of the calk is flat throughout its area except for the wrench-receiving recesses or notches 1.

During fair weather when the track is dry, calks without spikes are used for both heels of the shoe but when the track is muddy, spiked calks may be very easily and quickly substituted in lieu of the flat calks. In Fig. 1, a single spiked calk has been shown in use and this calk is applied to the outer heel of the shoe so that the horse wearing the shoe will not be liable to cut one foot with the calk of the shoe worn on the other foot. In some cases, calks may be applied to both heels of a shoe. It should also be noted that if desired, the insert may be formed as shown in Fig. 5, wherein the insert is solid, the recesses 6 and the threaded socket shown in Fig. 3, as well as in Fig. 4, being omitted. This form of insert serves as a permanent calk for fast tracks and shoes equipped with such calks or inserts are

used upon horses not intended to run upon muddy tracks.

Having thus described the invention, what is claimed is:

1. A horse shoe having heel portions formed with depending enlargements, inserts of hard metal cast into the enlarged heel portions and each being of frusto conical shape and formed at its lower end with a flat disc-like head in flat face to face engagement with the under face of the heel portion in which its frusto conical portion is embedded, said head being formed at its periphery with recesses for receiving portions of the enlargement and holding the insert against turning movement, a calk having a disc-like body, a threaded stem carried by the body and screwed into the socket, a locking washer about the stem, the inner face of the body being formed with a circular recess about the stem for receiving the locking washer, the outer face of the body being formed with wrench-receiving recesses, and a spike projecting from the outer face of the body in alignment with the stem.

2. A horse shoe having heel portions, inserts of hard metal cast into the heel portions and held against outward movement, each insert having a disc-like head at its outer end in face to face engagement with the underface of the heel portion in which the insert is mounted, each insert being formed with a threaded socket open at its lower end, and calks each having a disc-like body and a threaded portion for engaging in the socket of

the companion insert, the outer faces of the disc-like bodies being formed with wrench-receiving recesses.

3. A horse shoe having heel portions, inserts of hard metal cast into the heel portions and held against outward movement, each insert having a disc-like head at its outer end in face to face engagement with the under face of the heel portion in which the insert is embedded, each insert being formed with a threaded socket open at its lower end, calks, each calk having a disc-like body and a threaded stem extending centrally therefrom for engaging in the socket of the companion insert, and locking washers about the stems for holding the calks against turning in a loosening direction, the inner faces of the disc-like bodies being formed with annular recesses about the stems for receiving the locking washers.

4. A horse shoe having heel portions, inserts of hard metal cast into the heel portions and held against outward movement, each insert having a disc-like head at its outer end in face to face engagement with the under face of the heel portion in which the insert is embedded, each insert being formed with a threaded socket open at its lower end, calks, each calk having a disc-like body and a threaded stem extending centrally therefrom for engaging in the socket of the companion insert, and a spike extending outwardly from the disc-like body of one calk in alignment with the stem thereof.
